SHELF AND LAMP BASE COMBINATION

Alfred Landes, Rego Park, N. Y.

Application September 27, 1954, Serial No. 32,438

Term of patent 7 years

(Cl. D48—4)

Fig. 1

Fig. 2.

Fig. 3.

To all whom it may concern:

Be it known that I, Alfred Landes, a citizen of the United States, residing at Rego Park, county of Queens, State of New York, have invented a new, original, and ornamental Design for a Shelf and Lamp Base Combination, of which the following is a specification, reference being had to the accompanying drawing, forming a part hereof.

I claim:

The ornamental design for a shelf and lamp base combination, substantially as shown.
